CLAIM

The ornamental design for a valet, as shown and described.

DESCRIPTION

FIG. 1 is a front perspective view of a valet showing my new design;

FIG. 2 is a front elevational view thereof;

FIG. 3 is a right side elevational view thereof, the left side being substantially a mirror image thereof; and

FIG. 4 is a top plan view thereof.

The rear and bottom of the valet are substantially plain and unornamented.
